UNITED STATES PATENT OFFICE.

LEONARD D. KROFF AND PETER FRANTZ, OF STERLING, ILLINOIS, ASSIGNOR TO FIRST TRUST & SAVINGS BANK, TRUSTEE, OF STERLING, ILLINOIS.

GAME APPARATUS.

Application filed October 7, 1922. Serial No. 592,994.

To all whom it may concern:

Be it known that we, LEONARD D. KROFF and PETER FRANTZ, citizens of the United States, residing at Sterling, in the county 5 of Whiteside and State of Illinois, have invented certain new and useful Improvements in Game Apparatus, of which the following is a specification.

The present invention has for its objects 10 to provide means for retaining player pieces on game boards during their non-use, and especially during shipment, so that the player pieces may not become lost; to provide a game apparatus with means to simulate a base ball field with pictures of the 15 players in customary positions thereon and the provision of dummy players for use on the field; another object of the invention is to provide the game board with a pair of 20 pointers pivoted at each side of the field in two corner sections thereof with means to cooperate with the pointers to indicate "strikes" and "balls" during the playing of the game.

25 In its more detailed nature, the invention also includes those novel features of construction, combination and arrangement of parts, all of which will be first fully described and then be specifically pointed out in 30 the appended claims, reference being had to the accompanying drawings, in which:

Figure 1 is a perspective view of a portion of a game board with the player pieces locked in place.

35 Figure 2 is a top plan view of the same, the player pieces having the bottoms cut off.

Figure 3 is a longitudinal section on the line 3—3 of Figure 2, the player pieces being complete and locked in place.

40 Figure 4 is a view similar to Figure 3 with the locking slide withdrawn and the player pieces removed.

Figure 5 is a cross section on the line 5—5 on Figure 2.

45 Figure 6 is a cross section on the line 6—6 on Figure 2.

Figure 7 is a perspective view of the game apparatus complete.

In the drawings, in which like numerals 50 of reference designate like parts in all of the figures, 1 represents the frame of the game board to which is tacked or screwed, at 19, the game board proper 2. The game board proper 2 may be made of sheet metal 55 bent up, at 3, and flanged, at 4, to provide

a suitable rest on the frame 1 and also to provide a sufficient depression to bring the exposed surface of the player pieces within the shallow pan formed by the game board proper.

The plate 2, constituting the game board player, has ears 6 stamped from it and is provided with a slot 7 extending lengthwise in a direction at right angles to the lengthwise direction of the ears 6. 8 is a sliding plate, one end of which slides between the ears 6 beneath the plate 2 and the other end of the plate is transversely slotted, as at 9, to provide a portion 10 which is bent downwardly away from the plate 2 and constitutes a resilient member to which the finger button 12 has its shank 13 riveted, as at 14. The resiliency of the portion 10 of the plate 8 holds the finger piece 12 against the plate 2 with sufficient retaining friction to maintain the plate 8 at any position it may be placed when sliding the finger piece 12 along the slot 7.

The plate 2, constituting the game board proper, is provided with holes 5 and the slide 8 has corresponding holes 11 registering with the holes 5 when the finger piece 12 is at the far end of the slot 7. (See Figure 4.) These holes 5 and 11 when in alignment admit the shanks 16 of the player pieces, (during plays) in the inverted position, the bases 15 of the player pieces lying on the top surfaces of the plate 2. (See Figures 1, 3 and 5.) When the finger piece 12 is slid to the inner limit of the slot 7 the holes 11 move out of alignment with the holes 5, (see Figure 2) and project the edge of the plate 8 and the edges of the holes 11 into the annular grooves 18 formed between the collars 17 and bases 15 of the player pieces to thereby lock securely the player pieces in place against accidental displacement when shipping the game or when carrying it around.

Referring to Figure 7, it will be seen that the dummy players, when in resting place, are normally turned upside down, so that their bases 15 are visible and grouped together in the manner shown. Adjacent to each group, on the upper surface of the game board 2, there is a picture of a bench 20 with players seated thereon, thus simulating one of the features of actual practice in the playing of baseball. The actual conditions of the game are further approx-

imated or simulated by the provision of pictures of players 21 located in their customary positions on the baseball field shown on the top surface of the game board. This adds zest to the game, in the use of the toy, and in this connection it will be further observed that the field is laid out to closely resemble the familiar features and appearance of an ordinary baseball field. The two groups of dummy players occupy two corner sections of the field, as shown, and in the other two corner sections there are indicators for "strikes" and "balls" at one corner and "runs" and "outs" at the other corner, each indicator consisting of a pivot at 22 with two hands or pointers 23 and 24 thereon, and circles 25 within which are disposed the numerals and the words "strikes" and "balls" and "runs" and "outs", as shown. Thus one indicator is at the same side of the field as one group of dummy players, and the other indicator is at the other side in line with the other group of dummy players. It will be understood, of course, that the positions which the dummy players will occupy on the diamond of the base-ball field, in the use of the toy, are determined by the rotation of the cylinder 26 by the push button 27 in the manner fully explained in the application of Leonard D. Kroff, filed April 20, 1920, Serial No. 375,211, of which the present invention is an improvement.

What we claim is:

1. In game apparatus, a game board having holes to receive the shanks of player pieces, player pieces having bases and shanks and having annular grooves, a slide with holes adapted to register with those of the board when in one position and to be out of register therewith when in another position whereby to release or retain the player pieces, means by which said slide may be shifted, the edge of each hole in the slide being adapted to have locking engagement with the groove of a player piece.

2. In game apparatus, a game board having holes to receive the shanks of player pieces, player pieces having bases and shanks and having annular grooves, a slide with holes adapted to register with those of the board when in one position and to be out of register therewith when in another position whereby to release or retain the player pieces, and means to retain said slide in either of its positions, the edge of each hole in the slide being adapted to have locking engagement with the groove of a player piece.

3. In game apparatus, a game board having holes to receive the shanks of player pieces, player pieces having bases and shanks

and having annular grooves, a slide with holes adapted to register with those of the board when in one position and to be out of register therewith when in another position whereby to release or retain the player pieces, and means to retain said slide frictionally in either of its positions, the edge of each hole in the slide being adapted to have locking engagement with the groove of a player piece.

4. In game apparatus, a game board having holes to receive the shanks of player pieces, player pieces having bases and shanks, a slide with holes adapted to register with those of the board when in one position and to be out of register therewith when in another position whereby to release or retain the player pieces, and means to retain said slide frictionally in either of its positions, said means comprising a slit in the slide and a bent down springy portion with a headed finger button mounted thereon and operable in a slot in the board.

5. In game apparatus, the combination of means to provide the field upon which the game is played, dummy players, and provisions on said field whereby the dummy players when at rest are supported upside down with only the bases thereof exposed to view, said provisions comprising holes arranged in two groups, with a dummy player in the hole, and locking means to prevent displacement of said dummy players from said holes while leaving the bases of the players exposed to view.

6. In game apparatus, the combination of means to provide a field on which the game is played, dummy players, and devices to lock the dummy players in resting position when not in use and with their bases exposed to view.

7. In game apparatus, the combination of means to provide a field on which the game is played, dummy players, and devices to lock the dummy players in resting position when not in use, such devices comprising a plate with holes therein for the dummy players and means to shift the plate edge-wise to engage and disengage the players.

8. In game apparatus, the combination of means to provide a field on which the game is played, dummy players, and devices to lock the dummy players in resting position when not in use, said devices comprising a plate at each of two corners of the field, with holes in each plate for the players, and means on the field to manually control said plates.

LEONARD D. KROFF.
PETER FRANTZ.
